Patented Dec. 15, 1970

219,446

MARINE WASTE HOLDING TANK

Edward F. Arros, 1 Hetcheltown Road,
Scotia, N.Y. 12302

Filed Feb. 19, 1968, Ser. No. 10,638

Term of patent 14 years

Int. Cl. D23—01

U.S. Cl. D23—2

FIG. 1

Des. 219,446

PAGE 2

FIG. 2

FIG. 3

FIG. 4

FIG. 5

FIG. 1 is a perspective view of a marine waste holding tank showing my new design;

FIG. 2 is another perspective view thereof taken from the end opposite that shown in FIG. 1;

FIG. 3 is a top plan view thereof;

FIG. 4 is a side elevational view thereof; and

FIG. 5 is an elevational view taken from the end shown in FIG. 2.

I claim:

The ornamental design for a marine waste holding tank, substantially as shown and described.
